UNITED STATES PATENT OFFICE.

ADOLPH SOMMER, OF HABERFIELD, NEAR SYDNEY, AND ALBERT GEORGE HOOD, OF NARRABEEN, NEAR SYDNEY, NEW SOUTH WALES, AUSTRALIA, ASSIGNORS OF ONE-THIRD TO EDWARD ROBERT STERLING, OF SEATTLE, WASHINGTON.

INTERNAL-COMBUSTION ENGINE.

Application filed August 7, 1926, Serial No. 127,885, and in Australia August 10, 1925.

This invention has been specially devised to provide novel combinations and arrangements of mechanical parts which enable internal combustion engines of either the two or 5 the four cycle type to be constructed as improved double-acting internal combustion engines having comparatively greater power than such engines of given size and weight heretofore produced and wherein is more 10 equal distribution of the load on the working parts of such engines than heretofore.

An improved double-acting internal combustion engine constructed according to this invention has its cylinder or cylinders and 15 valves and kindred parts of ordinary construction but each cylinder is longer and the piston is hollow and of greater length than ordinarily and constitutes a second cylinder which is around a fixed piston or piston headed 20 abutment having a fuel valve therein and supported by hollow walls or stanchions from the engine frame and between which stanchions the piston rod is free to move. From the lower edge of the apron of the piston a piston 25 rod connects to the ordinary crosshead or crank of the engine.

But in order that this invention may be readily understood and embodied in practice it will now be described incorporated in a well 30 known make of engines as illustrated in the more or less schematic drawings accompanying and forming part of this complete specification. Figs. 1 and 2 are respectively sectional elevations at right angles to one another of the relevant units of a two-cycle Diesel engine having embodied therein these 35 present improvements while Figs. 3 to 6 show details thereof.

The cylinder 7 with usual valvular accessories has a long hollow piston 8 which has two external lugs 9 in or fast to which are pins or gudgeons 10 wherefrom a bifurcated piston rod 11 connects to a cross head 12 having guides and a connecting rod to a crank 45 and shaft of ordinary construction. The hollow of said piston 8 constitutes a second cylinder 13 around an abutment or stationary piston 14 supported by stanchions 15 (between which the piston rod 11 is free to reciprocate) 50 from the engine frame 16. Between the piston 8 and the stationary piston 14 a liner 21 is positioned and grooves 22 provided in the internal wall of said piston 8 to allow water to circulate from point 23 where telescopic rods

(not shown) from a water supply are affixed 55 to the hollow of said piston. The cylinder 7 has a plurality of scavenge ports 17 and 18 and the piston 8 has ports 19 therein which are adapted at arbitrary points of the piston 8) stroke to juxtapose the ports 18 and so 60 open air access to cylinder 13 and permit scavenging thereof. The said piston 8 also uncovers ports 17 to permit the scavenging of cylinder 7.

The cylinder cover 20 may contain the usual 65 fuel valves and starting valves or said valves might be otherwise housed and they and consequential operating integers may be of any suitable construction and working but as these do not form any part of this present invention 70 no further description is called for.

The second or piston cylinder 13 in present preferred construction has its fuel and starting valves in abutment piston 14 as indicated at 24 but as their valves and the manner in 75 which they are operated is common engineering knowledge and they do not form part of this present invention they are not described or shown herein.

During the normal firing (or outward) 80 stroke of piston 8 in the cylinder 7 air is compressed between the inner face of piston head 8 and the face of abutment piston 14 in the piston cylinder 13 and on completion of such stroke fuel is admitted to said cylinder 85 13 through the inlet or fuel valve as indicated at 24 and at the commencement of the return stroke ignition takes place assisting the synchronous inward compression stroke of piston 8 in cylinder 7 so giving additional momentum or power to the engine as well as relieving strain on the engine working parts by reason of this being accepted by abutment piston 14 and on completion of the respective strokes the scavenging air is admitted as 90 95 before explained.

In the present construction the piston 8 is of wrought iron or steel and the inner shell or liner 21 is of cast iron or other metal and the grooves or cavities 22 between the two 100 walls allow the circulation of cooling water.

It is to be clearly understood that the carrying into effect of this invention is now confined to the precise mechanical constructions described and illustrated so long as the natures and mechanical functions of its main parts are retained for many variations of the construction and arrangement of the

parts or integers will suggest themselves to those skilled in the art to which this invention appertains. It will be easily comprehended by the internal combustion engine designer, constructor and/or mechanic that the combination and arrangement of the essential or main part of this invention the long reciprocating hollow piston around an abutment piston may be usefully and simply applied to a four cycle Diesel engine and to ignition engines of two-cycle or Otto-cycle and to like internal combustion engines.

What we claim as our invention and desire to secure by Letters Patent is; —

- 15 1. In an internal combustion engine the combination of a fixed cylinder; a piston reciprocally mounted in said fixed cylinder, comprising a head and a cylindrical wall extending therefrom; a stationary piston positioned within the cylindrical wall of said movable piston; a liner located between the said stationary piston and the inner face of the cylindrical wall of said movable piston; grooves formed in said inner face of the said
- 20

cylindrical wall and communicating with a cavity formed in the head of said movable piston, adapted to receive a cooling medium therefor.

2. In an internal combustion engine the combination of a fixed cylinder; a piston reciprocally mounted in said fixed cylinder, comprising a head and a cylindrical wall extending therefrom; a stationary piston positioned within the cylindrical wall of said movable piston; a liner located between the said stationary piston and the inner face of the cylindrical wall of said movable piston; grooves formed in said inner face of the said cylindrical wall and communicating with a cavity formed in the head of said movable piston, adapted to receive a cooling medium therefor; and means for supplying a cooling medium to said grooves.

In testimony whereof we have signed our names to this specification.

ADOLPH SOMMER.
ALBERT GEORGE HOOD.
